2,140,580

MEANS FOR FITTING BRAKE BANDS
AND LININGS

Milton E. Hatchman, Chicago, Ill.

Application August 17, 1934, Serial No. 740,275

13 Claims.

(Cl. 51—241)

My invention relates to means for fitting brake bands and linings for effective cooperation with the associated drums, and is particularly designed for operation on the brakes of an automobile. It is an object of my invention to provide in a device of this type a new and improved form and arrangement of parts by which a grinding operation can be readily effected upon the outer faces of the brake linings, and by which the proper adjustment of the parts may be readily determined and readily effected for assuring the proper grinding of the linings.

It is one of the objects of my invention to provide an improved device of this type so constructed and arranged as to be capable of effective use for effecting the desired grinding of the linings after such linings are attached in operative position on the car, this result being attained preferably by the use of grinding means adapted to be revolved concentrically about the axle. It is accordingly one of the objects of my invention to provide improved means for mounting the required grinding mechanism in centered position on the axle.

It is another object of my invention to provide improved means for adjusting the grinding member toward and from the axle, preferably through the medium of a micrometer screw, whereby the grinding mechanism may readily be advanced or retracted by the desired number of thousandths of an inch, or other suitable unit of measurement, and then be brought back again to the original position if desired.

It is one of the objects of my invention to provide improved gauging means which can be set first to the desired position by application to the brake drum and can then be employed to advantage for the initial setting of the grinding mechanism by which the faces of the brake linings are to be dressed.

It is another object of my invention to improve devices of this type in sundry details hereinafter pointed out. The preferred means by which I have accomplished my several objects are illustrated in the drawings and are hereinafter specifically described. That which I believe to be new and desire to cover by Letters Patent is set forth in the claims.

In the drawings.—

Fig. 1 is a side face view of my improved device, partly in section, showing the gauging means in position for the initial adjustment of the grinding head with respect to the axis about which said head is to be rotated;

Fig. 2 is a face view of my improved gauging

means in the brake drum of a wheel, the drum being indicated diagrammatically by dotted lines;

Fig. 3 is a detail view, being substantially a section taken at line 3—3 of Fig. 1;

Fig. 4 is a detail view upon an enlarged scale, 5 as seen at line 4—4 of Fig. 2;

Fig. 5 is a view of my improved mechanism mounted upon an axle in position for grinding the brake linings fixed on the outer faces of the brake bands or shoes;

Fig. 6 is an enlarged detail view, partly in section, showing the construction and arrangement of the split sleeve which when fixed upon the axle serves as a bearing for the grinding mechanism; and

Figs. 7 and 8 are cross sectional views taken at line 7—7 and line 8—8 respectively of Fig. 6.

Referring now to the several figures of the drawings, in which corresponding parts are indicated by the same reference characters, 10 and 11 indicate two plates rotatably connected together, such connection in the construction shown being effected through the medium of a sleeve or collar 12 extending outwardly from one face of the plate 11 and fitting snugly in a central opening in the plate 10 which in the arrangement shown is in the form of a ring. As is best shown in Fig. 2, the plate 11 is in the form of a spider having a central opening therethrough conforming to the opening through the collar 12, the plate 11 and collar 12 being formed integrally in the arrangement shown. Upon the outer ends of the arms provided by the spider form of the plate 11, I have pivotally mounted three arms 13, 14 and 15 at points near their ends, the axes 35 upon which said arms are mounted being located at the same distance from the axis upon which the plates 10 and 11 are rotatably connected, and being equally distributed about said axis. The shorter end portions of the arms are 40 connected by means of links 16, 17 and 18 with the plate 10, the three links being of the same length and being connected with the plate 10 at points equidistant from the axis upon which plates 10 and 11 are rotatably connected, such 45 points of connection of the links with the plate 10 being also equally spaced about said axis. As will be readily understood, when the plate 10 is rotated in clockwise direction in Fig. 2 with respect to the plate 11, the arms 13, 14 and 15 are 50 swung outwardly away from each other. Inasmuch as the three arms are all of the same length and are pivotally mounted at the same relative points therealong, it will be evident that as the arms are swung inwardly or outwardly the outer 55

ends of the arms are kept at all times at equal distances from the axis upon which the plates 10 and 11 are connected.

The connection between the arms and the links is effected in each instance by the use of a screw 19 having a thumb nut 20 thereon suitable for effective manipulation for tightening the bolt by hand for holding the link and the arm from swinging with respect to each other. In 10 the arrangement shown, a lock washer 21 is employed whereby effective pressure can be applied between the arms and the links without complete frictional locking of the parts together.

As is best shown in Fig. 4, the pivotal connections between the arms and the plate 11 is in each instance effected by the use of a screw 22 which passes through an opening in the arm and has screw-threaded connection with the plate, such screw being held in position by means 20 of a second screw 23 passing through a portion of the plate 11 and having screw-threaded connection with the screw 22.

By my improved arrangement as above described, in which the pivotal connections of the 25 parts is effected by special means for holding the parts in true centered position even when the connection is maintained loose enough for permitting relative movement of the connected parts, I have provided gauging means which is 30 very accurate and which can be relied upon for measuring accurately and quickly the size of a drum such as the brake drum 24 shown in dotted lines in Fig. 2. When the device as shown in Fig. 2 has been expanded for light contact of 35 the arms with the face of the circular drum, and when the nuts 20 have then been tightened for holding the parts against further adjustment, the gauge can be readily removed from the drum ready for use as a pattern or templet as may be 40 required.

As is best shown in Figs. 1 and 3, the means for mounting my improved grinding mechanism upon an axle comprises a split sleeve 25 of bronze mounted within a casting 26 also in the form of a 45 split sleeve having lugs 27 formed therewith connected by a machine screw 28 by which the cast sleeve 26 can be tightened about the split sleeve 25. At one side, the cast sleeve 26 is provided with a slide box 29 extending longitudinally of 50 the sleeve, in which is mounted a slide block 30 provided with a heavy bar 31 positioned radially with respect to the sleeve. In the construction shown, the slide block 30 is held in position by means of screws 32 adapted to be mounted in 55 any one of a plurality of openings along the slide box, the arrangement being such that the bar 31 can be adjusted and held firmly in position through a considerable range longitudinally of the sleeve 26.

60 Upon the bar 31, I have mounted a split bracket 33 the opposite side portions of which are connected by means of a machine screw 34 which when tightened holds the bracket in adjusted position longitudinally of the bar 31. Upon the bracket 33, in turn, I have mounted a head 35 in 65 the form of a casting having a sliding connection with the bracket. As is clearly shown in Fig. 1, the bracket 33 is provided with a lug 36 which has screw-threaded connection with a pin 37 which is 70 rotatably mounted in the head 35, the arrangement being such that upon rotation of the pin 37 the head 35 is moved longitudinally of the bar 31. The pin 37 is provided with an enlarged head portion 38 upon which I have provided a series of 75 graduations. In the preferred arrangement, the

threads on the pin 37 are arranged 40 to the inch, and 25 graduations are provided so that upon the movement of the pin 37 from one graduation to the next the head 35 is moved one-thousandth of an inch.

Upon the head 35, I have provided an electric motor 39 of any approved type equipped with a driving shaft 40 having an aluminum grinding head 41 mounted upon its outer end, such grinding head 41 being adapted to have an abradant 10 surfacing means of any approved type mounted thereon.

The means for mounting the grinding mechanism upon an axle comprises a split sleeve 42 of a size suitable for a snug working fit within the 15 bronze sleeve 25 above described. In preparation of an axle for reception of my improved grinding mechanism, split collets 43 and 44 are first placed lightly in position upon the axle, such as the axle 45 as shown in Fig. 6. The split sleeve 42 20 is then slid into position over the collets, with the opening in the wall of the sleeve located opposite the openings in the sides of the collets, as is best shown in Fig. 8. The sleeve 42 is then tightened about the collets, serving to tighten 25 the collets also upon the axle 45, such tightening being effected by the use of a machine screw 46 rotatably mounted in the sleeve 42 at one side of the opening and having screw-threaded connection with the opposite side portion. I have found 30 that the size and shape of the axles of automobiles ordinarily in use are sufficiently uniform with respect to the front and rear axles and with respect to the axles of different makes as to enable me to fit my improved split sleeve 42 upon 35 an axle by the use of the proper collet selected from a fairly small number of collets, not more than about 20 of such parts being required.

When a car is brought in for having its brakes 40 ground, the wheel is first taken off and the drum 45 on the wheel is shaped and turned to true cylindrical form. The gauge is then inserted as shown in Fig. 2 and the nuts 20 are tightened for maintaining the arms in the desired expanded relation. The gauge is then set in position in the split sleeve 25, the sleeve portion 42 of the gauge being of such size as to have a snug working fit in said sleeve. The micrometer screw arrangement 37, 38 is then set at zero, after which the screw 34 is loosened and the device as a whole is moved into position such that the grinding face of the head 41 is brought lightly into engagement with one of the arms of the gauge and the screw 34 is then tightened for holding the parts in the desired adjusted position. After the removal of the wheel, the sleeve 42 is placed in 50 position upon the axle and secured in position by tightening the screw 46 as above described. The micrometer gauge is then turned for providing the desired anchor clearance, the amount of 55 such clearance depending upon conditions known in advance in connection with different cars. The grinding mechanism is then placed in position as shown in Fig. 5, with the bronze sleeve 25 sliding into position upon the split sleeve 42 60 fixed upon the axle of the car. The grinding head 41 is then preferably given a complete revolution about the axle, such revolution being effected with the brake shoes 47 and linings 48 retracted or drawn inwardly to the limit of their 65 movement, the spreading mechanism for the shoes or bands being entirely disconnected from the operating rods and levers if necessary for assuring the desired contraction of the parts. In such revolution of the grinder head 41 about 70 75 75

the shoes and linings, the workman can determine whether or not the shoes and linings are properly adjusted and can shape such parts by the use of suitable tools if they have become distorted in use. After the shoes and linings have been adjusted to approximately their true shape, the connections between the shoe spreading devices and the operating rods are adjusted for expanding the shoes to a slight extent for bringing the linings lightly into contact with the grinding head. The motor 39 is then started and the device is given a complete revolution slowly about the axle serving to dress off a very small portion from the outer faces of the linings. If an inspection after the complete revolution shows that the linings have not been completely shaped, the connections of the operating rods can be adjusted for expanding the shoes the required additional amount and a second revolution of the grinding mechanism with the motor operating can be made for effecting the desired accurate shaping of the shoes with respect to the drum.

While I prefer to employ the form of mechanism as above described, it is to be understood that my invention is not limited thereto except so far as the claims may be so limited by the prior art.

I claim:

1. In a mechanism of the type described, the combination of a split sleeve, a split collet in each end of the sleeve, means for tightening the sleeve and the collets about an axle, a second sleeve rotatably mounted on said first named sleeve, a bar projecting from one side of said second sleeve substantially radially thereof, a head slidably mounted on said bar, and grinding means operatively mounted on said head.

2. In a mechanism of the type described, the combination of a split sleeve, a split collet in each end of the sleeve, means for tightening the sleeve and the collets about an axle, a second sleeve rotatably mounted on said first named sleeve, a bar projecting from one side of said second sleeve substantially radially thereof and adjustable longitudinally of the sleeve, a head slidably mounted on said bar, and grinding means operatively mounted on said head.

3. In a mechanism of the type described, the combination of a bearing member, means for rotatably mounting said bearing member in concentric position about an axle, a bar projecting from one side of said bearing member substantially radially thereof, a bracket mounted on said bar and held against rotary movement with respect to the bar but free to move longitudinally of the bar, means for holding said bracket in adjusted position on said bar, a head mounted on said bracket and adjustable thereon toward and from said bearing member, adjustable means for moving said head with respect to said bracket and holding it in adjusted position, and grinding means operatively mounted on said head.

4. In a mechanism of the type described, the combination of a bearing member adapted to be rotatably mounted on an axle, a bar projecting from one side of said bearing member substantially radially thereof, a bracket mounted on said bar, and adjustable therealong, means for holding said bracket in adjusted position on said bar, a head mounted on said bracket and slidable thereon toward and from said bearing member, screw-threaded means for moving said head with respect to said bracket and holding it in adjusted position, and grinding means operatively mounted on said head.

5. In a mechanism of the type described, the combination of a bearing member adapted to be rotatably mounted on an axle, a bar projecting from one side of said bearing member substantially radially thereof, a bracket mounted on said bar, and adjustable therealong, means for holding said bracket in adjusted position on said bar, a head mounted on said bracket and slidable thereon toward and from said bearing member, a pin rotatably mounted in said head and held against longitudinal movement with respect thereto and having screw-threaded connection with said bracket for giving said head a movement longitudinally of the bar, scale and index means on said pin and said head for showing the distance through which said head moves with respect to the bracket, and grinding means operatively mounted on said head.

6. In a mechanism of the type described, the combination of a split sleeve, means for tightening said sleeve about an axle, a second split sleeve rotatably mounted on said first named sleeve, means for tightening said second split sleeve about said first named sleeve so as to have a snug working fit thereabout, a bar projecting from one side of said second sleeve substantially radially thereof, a head slidably mounted on said bar, and grinding means operatively mounted on said head.

7. In a mechanism of the type described, the combination of a split sleeve, means for tightening said sleeve about an axle, a second split sleeve rotatably mounted on said first named sleeve, a third split sleeve mounted on said second sleeve, means for tightening said third sleeve on said second sleeve and serving to give said second sleeve a snug working fit on said first sleeve, a bar mounted on said third sleeve in substantially radial position thereon, a head slidably mounted on said bar, and grinding means operatively mounted on said head.

8. In a mechanism of the type described, the combination of a bearing member, means for rotatably mounting said bearing member in concentric position about an axle, a bar mounted on said bearing member in radial position with respect thereto and movable transversely of the bar into adjusted position thereon, means for holding said bar in adjusted position with respect to the bearing member, a head slidably mounted on said bar, and grinding means operatively mounted on said head.

9. In a mechanism of the type described, the combination of a bearing member, means for rotatably mounting said bearing member in concentric position about an axle, a slide-box on one side face of said bearing member longitudinally thereof, a block slidably mounted in said slide-box, a bar of non-round shape mounted on said block in radial position with respect to said bearing member so as to be movable transversely of the bar into adjusted position with respect to the bearing member, means for clamping said block in adjusted position with respect to said bearing member, a head slidably mounted on said bar so as to be held against rotary movement with respect to the bar, means for holding said head in adjusted position with respect to said bar, and grinding means movably mounted on said head so as to be adjustable longitudinally of said bar toward and from said bearing member.

10. In a mechanism of the type described, the combination of a bearing member, means for rotatably mounting said bearing member in concentric position about an axle, a slide-box on one

- side face of said bearing member longitudinally thereof, a block slidably mounted in said slide box, a bar of non-round shape mounted on said block in radial position with respect to said bearing member so as to be movable transversely of the bar into adjusted position with respect to the bearing member, means for clamping said block in adjusted position with respect to said bearing member, a head slidably mounted on said bar so as to be held against rotary movement with respect to the bar, means for holding said head in adjusted position with respect to said bar, grinding means movably mounted on said head so as to be adjustable longitudinally of said bar toward and from said bearing member, and screw-threaded connections between said grinding means and said head for holding the grinding means in adjusted position with respect to the head.
11. In a mechanism of the type described, the combination of a sleeve, means for rotatably mounting said sleeve in concentric position about an axle, a slide box on one side face of said sleeve longitudinally thereof, a block slidably mounted in said slide box, a bar mounted on said block in substantially radial position with respect to

said sleeve, a head slidably mounted on said bar, and grinding means operatively mounted on said head.

12. In a mechanism of the type described, the combination of a bearing member, means for rotatably mounting said bearing member in concentric position about an axle, a bar mounted on said bearing member in substantially radial position thereon, a head mounted on said bar so as to be adjustable toward and from said bearing member, an electric motor mounted on said head, and a grinding member mounted on said motor and rotatable about an axis at right angles to the axis of said bearing member.

13. In a mechanism of the type described, the combination of a bearing adapted to be rotatably mounted on an axle, a bar projecting from one side of said bearing substantially radially thereof, a bracket mounted on said bar and adjustable therealong, means for holding said bracket in adjusted position on said bar, a head mounted on said bracket and adjustable thereon longitudinally of the bar, and grinding means operatively mounted on said head.
